JOHN P. MCCLIMANS AND HOWARD S. CRESS, OF DULUTH, MINNESOTA

METHOD AND APPARATUS FOR COATING SURFACES

Application filed April 16, 1924. Serial No. 706,966.

This invention relates to new and improved method and apparatus for coating surfaces and more particularly to a method and apparatus for applying to surfaces, a coating of material rendered liquid by heat.

A particular application of our invention consists in the application of liquid sulphur to the walls of tanks or the like for the purpose of acid proofing such walls. The acid proofing of walls by means of a sulphur coating has been used in the past, the sulphur being melted in the tanks and applied to the walls by being thrown or splashed against the wall. This method of application is not satisfactory because the coating is unevenly applied and is applied in separate small amounts which do not adequately adhere to each other and to the wall, so that the coating readily breaks away from the wall in irregular patches.

While this one use of our method and apparatus will be particularly described in detail, it is to be understood that it may be used in the application of any coating of material rendered liquid by the application of heat, among which may be mentioned various bituminous or other compounds.

It is an object of the present invention to apply a new and improved method and apparatus whereby a liquid may be applied while heated to coat a surface in such manner as to provide a uniform coating applied with sufficient force to cause it to adhere to the surface.

It is a further object to provide means and method of this character in which the material is applied by gas under pressure and the gas and liquid are both heated immediately adjacent their point of application.

Other and further objects will appear as the description proceeds.

We have illustrated a preferred embodiment of our invention in the accompanying drawings, in which—

Figure 1 is a view of the apparatus, the heating chamber and housing being shown in section;

Figure 2 is a view of the heating chamber housing as seen from above; and

Figure 3 is a section taken on line 3—3 of Figure 1.

The gas hose 11 is connected by coupling 12 to the pipe 13 which has a portion 14 extending within the gas chamber 15. The gas discharge pipe 16 extends from the chamber 15 and its inner portion 17 extends into the chamber beyond the ends of the pipe 14. Gas discharge pipe 16 is connected by T 18 with the liquid discharge pipe 19. The discharge 60 nozzle 20 extends from the T 18 in line with the pipe 16. The lower end of the liquid carrying pipe 19 extends into the bucket or tank 21 in which the liquid is contained.

The gas chamber 15 and the adjacent portion of the liquid pipe 19 are enclosed in the heat retaining housing 22 which may be formed of asbestos or similar material. Upon either side of the chamber 15 and pipe 19 are located the two resistance elements 23 and 24. These elements are connected in series by the wire 25 and are connected to any suitable source of electrical current by means of wires 26 and 27.

In the use of the apparatus by our method, 75 the bucket or tank 21 will be filled with the material to be applied. This material will have been previously heated in a general supply tank, to such a degree as to render it substantially fluid. The flow of gas under 80 pressure is introduced from hose 11 into the gas chamber 15 through the extended pipe 14. By the term gas, we mean to include compressed air or steam or any suitable gas under pressure. The gas under pressure takes a 85 circuitous path through the chamber 15 and passes out through the discharge pipe 17 and across the T 18 through the nozzle 20. The circuitous path in the gas chamber causes the gas to be retained in such chamber for an 90 appreciable period of time during which it is heated by means of the heat derived from the resistance elements 23 and 24.

As the gas flows out across the T 18, it induces a flow of the coating material 95 through the pipe 19. This material is also further heated in that portion of the pipe 19 extending within the housing 22 adjacent the heating elements. Both the gas and liquid are thus heated immediately before 100

their junction and their application to the surface to be coated.

The coating is applied evenly by moving the nozzle to distribute the material as desired over the surface. It may be applied with any desired force by controlling the pressure of the gas, so that it may be caused to firmly adhere to the surface of the material to be coated. It will be understood that if highly heated steam is used as the gas for applying the liquid, it may be unnecessary to apply any heat by means of the electrical resistance element. In this case, the steam in passing through the gas chamber will heat the liquid in the adjacent pipe 19.

We have illustrated one preferred form of our invention by way of example, but it is to be understood that we contemplate such changes and modifications as come within the spirit and scope of the accompanying claims.

We claim:

1. Apparatus for applying a liquid coating, said apparatus comprising a gas chamber, a gas supply pipe leading to the chamber, a gas discharge pipe leading from the chamber, a liquid supply pipe connected to the gas discharge pipe in such manner that the flow of liquid is induced by the flow of gas, a portion of the liquid supply pipe extending adjacent the gas chamber and means for heating the gas chamber and the said portion of the liquid supply pipe.

2. Apparatus for applying a liquid coating, said apparatus comprising a gas chamber, a gas supply pipe leading to the chamber, a gas discharge pipe leading from the chamber, a liquid supply pipe connected to the gas discharge pipe in such manner that the flow of liquid is induced by the flow of gas, a portion of the liquid supply pipe extending adjacent the gas chamber, a housing for the gas chamber and said portion of the liquid supply pipe and electrical heating elements enclosed in said housing.

3. Apparatus for applying a liquid coating, said apparatus comprising a gas chamber, a gas supply pipe leading to the chamber, a gas discharge pipe leading from the chamber, the gas supply pipe and discharge pipe extending into the gas chamber with their ends overlapping whereby the gases are caused to take a circuitous path in the chamber, a liquid supply pipe connected to the gas discharge pipe in such manner that the flow of liquid is induced by the flow of gas, and means for heating the gas chamber.

Signed at Duluth, Minnesota, this 1st day of April, 1924.

JOHN P. McLIMANS.
